C. WIRT.
ELECTRIC LIGHTING APPARATUS.
APPLICATION FILED JAN. 5, 1915.

1,238,868.

Patented Sept. 4, 1917.

UNITED STATES PATENT OFFICE.

CHARLES WIRT, OF PHILADELPHIA, PENNSYLVANIA, ASSIGNOR TO WIRT COMPANY, OF PHILADELPHIA, PENNSYLVANIA, A CORPORATION OF MAINE.

ELECTRIC-LIGHTING APPARATUS.

1,238,868.

Specification of Letters Patent.

Patented Sept. 4, 1917.

Application filed January 5, 1915. Serial No. 551.

To all whom it may concern:

Be it known that I, CHARLES WIRT, a citizen of the United States, residing in the city of Philadelphia, State of Pennsylvania, have 6 invented certain new and useful Improvements in Electric-Lighting Apparatus, of which the following is a specification.

My invention relates to means for regulating the amount of light given by a plurality 10 of electric lamps, particularly electric incandescent lamps, the quantity of light ranging from that furnished by all the lamps at full voltage to that of one or more lamps at considerably lower voltage.

15 In one of its forms my invention is embodied in simple and compact structure whereby any number of a cluster of lamps may be brought into or cut out of circuit, with means for cutting into or out of the circuit of one or more of the lamps resistance to vary the current in said lamp or lamps.

20 By my invention a great range in the quantity of light produced by a predetermined number of light producing units is 25 possible at high efficiency in current consumption. This results from the fact that some of the units operate only upon full voltage of the supply circuit, without interposed resistance, and the amount of light is 30 reduced by cutting such units successively out of circuit, and the final unit or units dimmed by interposed resistance. Therefore energy is wasted only when such resistance is in circuit.

35 My invention is therefore applicable to theaters or the like where great variations in lighting may efficiently be obtained.

40 And it will be understood that the individual lamps hereinafter described may be supplanted by a group of lamps, each group being controlled as described as if it were a single lamp.

45 For an illustration of one of many forms my invention may take reference is to be had to the accompanying drawing, in which:

Figure 1 is a sectional view, some parts in elevation, of controlling means for a lamp cluster.

50 Fig. 2 is a plan view of a resistance element and associated parts.

Fig. 3 is a bottom plan view of a brush or contact member of the switching mechanism.

Fig. 4 is a side elevational view of the brush or contact with its associated operating means.

Fig. 5 is a diagrammatic view illustrating an arrangement of the electrical circuits.

Figs. 6 and 7 are plan and edge views, respectively, of an element of the contact member or brush.

Referring first to Fig. 5, which illustrates one mode of connection suitable for the practice of my invention, 1 and 2 represent the two conductors of any suitable supply circuit, ordinarily a constant potential circuit 65 delivering either direct or alternating current. The conductor 1 connects at 3 with the conductor 4 which connects with one terminal of each of the lamps L_r , L^1 , L^2 and L^3 adapted to form a lamp cluster for any 70 desired illumination purposes, the lamp L_r being regulable while the lamps L^1 , L^2 and L^3 , are connected to operate only at full voltage of the supply circuit. The supply conductor 2 connects with the movable contact 60 or brush member 5 which is adapted to engage the contacts 6, 7, 8, 9, 10, 11 and 12, the brush member 5 having such angular extent that it is adapted to simultaneously engage 75 at least four of these contacts, when there are 80 four lamps.

A suitable resistance conductor R has its one terminal connected to the contact 6 and its other terminal to the contact 9, the contacts 7 and 8 being connected to intermediate 85 points of the resistance R . The other or remaining terminal of the lamp L_r is connected to the contact 9, and the remaining or other terminals of lamps L^1 , L^2 and L^3 are connected respectively with contacts 10, 11 90 and 12 by conductors 13, 14 and 15 respectively. The lamps are customarily held in suitable lamp sockets 16, 17, 18 and 19.

With the brush 5 in the position illustrated in Fig. 5, current is cut off from all the lamps. 95 By moving the brush 5 in a clock-wise direction it will first engage contact 6 whereupon current of smallest value will pass through lamp L_r causing it to operate at lowest candle power, due to the fact that entire resistance 100

R is in such case in series with it. Moving the brush into engagement with contact 7 causes a part of resistance R to be cut out of the lamp circuit with result that it will now 5 glow at a higher candle power; moving the switch into engagement with contact 8 cuts out another section of resistance R and causes an increase in intensity of light and when the brush 5 engages contact 9 resistance R is cut 10 out of circuit and the lamp L_r is connected directly across the supply conductors 1 and 2 and it therefore glows at its highest candle power. Moving the brush into engagement with contact 10, and remaining in engagement with contact 9, lamp L_r and lamp L¹ 15 will both glow at full candle power. Moving the brush 5 a further step into engagement with contact 11, and still continuing in engagement with contacts 9 and 10 causes 20 lamps L_r, L¹ and L² to glow at full candle power; and moving the brush 5 into engagement with contact 12, and still engaging contacts 9, 10 and 11, causes all four lamps to 25 glow at full candle power. Continuing the movement of the brush 5, lamp L_r will first be cut out of circuit, and then the others in succession.

Or the brush 5 may be operated in counter-clock-wise direction and the contacts engaged 30 in an inverse order to that described.

A similar embodiment of apparatus to operate in accordance with description of Fig. 5 is illustrated in Figs. 1 to 4 inclusive, in which reference characters corresponding to 35 those in Fig. 5 illustrate similar parts.

Within any suitable support or standard 20 is disposed a pipe 21 through which extend the supply conductors 1 and 2 which may be in the form of a flexible cord 22. A 40 spider member 23 is screw threaded on the upper end of the pipe 21 and clamps the spun metal shell member 24 against the member 20. Each of the lamp sockets 16, 17, 18 and 45 19, of which 19 is invisible, is supported upon the shell 24 by the usual nipples 25 upon which are threaded the nuts 26 engaging the inner wall of the shell 24.

Threaded into the spider 23 is the bolt 27 surrounded by the insulating washer 28 and 50 the insulating sleeve 29. Surrounding the insulating tube 29 is the metallic tube or sleeve 30 having the bottom flange 31 provided with the lug or ear 32 to which the supply conductor 2 is secured by screw 33.

The resistance conductor R may be disposed in any suitable way, but is here shown as wound in the form of a helical coil embedded in a cylinder of hardened plastic insulating material 34 having a central cylindrical opening through which the aforementioned tube 30 extends and having the outer sheet metal cover 35. It will be understood that neighboring convolutions of the resistance helix are separated and insulated 60

from each other. The contact bars 6 to 12 65 inclusive are also molded and held in the insulating material 34, their upper ends forming the contacts which are shown flush with the upper surface of the insulating material 34. Bars 6, 7, 8 and 9 have lugs or clips 36 70 by which they are connected to the resistance conductor R, bars 6 and 9 with opposite ends of the resistance R and bars 7 and 8 at points intermediate the ends. These contact bars, preferably at least bars 9, 10, 11 and 12, extend 75 below the lower face of the insulating material 34 and are provided with binding screws 37, 38, 39 and 40 by which the conductors connecting with one terminal of each lamp socket of each lamp are held in electrical 80 communication with the contact bars.

The cylinder or insulating material 34, in which the resistance conductor R is embedded is held between the flange 31 of tube 30 and the flange 41 on the metallic tube 42 85 engaged by the nut 43 threaded upon the tube 30.

Rotatable upon the tube 42 is the tube 44, confined beneath the nut 43, and secured at its lower end to the washer 45. Secured between the shoulder 46 on the tube 44 and the washer 45 are the disk of insulating material 47, insulating washer 48, and the four contact springs 49 suitably held or secured to the rotatable insulating disk 47 to which is secured the flanged pull chain or cord drum 50 to opposite sides of which are attached the pull chains or cords 51 and 52 for rotating the drum 50 and parts attached thereto.

The metallic contact springs 49 have the 100 preferably integral resilient downwardly inclined portions 53 terminating in the contacts 54 which form the movable contact member or brush 5 which are in permanent electrical communication with the conductor 105 2 through lug 32, tube 30, tube 42, and sleeve or tube 44 and washer 45. The super-imposed contact springs 49 are preferably secured to register in correct angular position by prick punchings 55.

Upon the nut 43 rests the insulating washer 56 upon which rests the metallic shell member 57 whose upper side is engaged by the nut 58 threaded upon the bolt 27 which holds the shell 57 at its lower edge against the cylinder of insulating material 34 within which is embedded the pin 59 engaging in a notch in the lower edge of shell 57 to prevent its rotation with respect to the member 34. Attached to the shell 57 is a tube 60 through 115 which the chains or cords 51 and 52 extend to the drum 50 and to the exterior for purposes of manipulation.

Resting upon the head 61 of the shell 24 is a shell 62, slotted at its upper edge at 63 to 120 receive the tube 60. A cover 64 for the shell 62 is held in place by the ornamental nut 65 adapted also to hold a shade.

From the foregoing description taken in connection with the description of Fig. 5 it will be understood that by pulling upon one or the other of the chains or cords 51 or 52 the drum 50 will be rotated as will also the brush contacts 54 attached thereto, these contacts 54 being all electrically connected to each other and to the conductor 2, as described, and adapted to engage the contacts 6 to 12 inclusive, the angular extent of the contacts 54 being sufficient at least to simultaneously engage as many contacts as there are lamps in the cluster.

It is obvious that my invention is in no way limited as to the number of lamps in the cluster and that as respecting even a single lamp, features of my invention are available. And it will be further understood that my invention is not limited to the regulation of candle power of only one of a plurality of lamps, but that more than one lamp of a group or cluster may have adjustable resistance associated therewith.

What I claim is:

25 1. A regulable lamp cluster comprising a support, a plurality of lamps, holders carried by said support, lamps for said holders, resistance conductor and a plurality of contact bars embedded in insulating material, a plurality of said contact bars connecting with said resistance, a lamp connected with said resistance, the remainder of said contact bars connecting with the remainder of said lamps, and relatively movable contact mechanism adapted to engage said contacts to vary the resistance in the circuit of a lamp and to bring the remainder of said lamps successively into circuit.

40 2. A regulable lamp cluster comprising a support, a plurality of lamp holders carried by said support, a resistance conductor, a series of contacts part of which are connected with said resistance conductor and others with said lamps, and relatively movable contact mechanism for engaging said contacts in succession and a plurality of them simultaneously.

3. A resistance conductor and a plurality of contact bars embedded in insulating material, a plurality of said bars connected to said resistance, said contact bars extending through said insulating material and forming contacts at one end and some of said bars having connectors at the other end, relatively movable contact mechanism adapted to engage the contact ends of said bars, and a plurality of lamps, said contact mechanism controlling the circuit of part of said lamps directly and of the remainder through said

55 60 resistance.

4. A resistance conductor and a plurality of contact bars embedded in insulating material, a plurality of said bars connected to said resistance, said contact bars extending

through said insulating material and forming contacts at one end and some of said bars having connectors at the other end, relatively movable contact mechanism adapted to engage the contact ends of said bars, a plurality of lamps, a supply circuit connection to one terminal of each of said lamps, the other terminals of said lamps connecting with said connector ends of said bars, and a supply circuit connection to said contact mechanism.

5. The combination with an electric lamp, of a stationary mass of insulating material, a resistance conductor embedded in said mass, a plurality of contact bars embedded in said mass, connections from a plurality of said bars to said resistance conductor, a rotatable contact controlling the circuit of said lamp and adapted to engage said bars, a cord actuated member attached to said rotatable contact, and a shell member inclosing said cord actuated member and said contact in a chamber formed by said shell member and said insulating material.

6. The combination with an electric lamp, of a single stationary helical coil of resistance conductor and contact bars disposed parallel to the axis of said coil and electrically connected to said coil, a mass of insulating material embedding said conductor and said contact bars, said bars having exposed ends, and a rotatable contact member controlling the circuit of said lamp and adapted to engage said contact bars.

7. The combination with an electric lamp, of a stationary helical coil of resistance conductor and contact bars disposed parallel to the axis of said coil, a mass of insulating material embedding said conductor and said contact bars, said bars having exposed ends, a rotatable contact member controlling the circuit of said lamp and adapted to engage said contact bars, and an axial supporting member for said insulating material, said contact rotatable upon said axial member.

8. A regulable lamp cluster comprising a shell, a plurality of lamps on the exterior thereof supported thereon, a stationary cylindrical mass of insulating material within said shell, a resistance conductor and a plurality of contact bars embedded in and supported by said insulating material, a plurality of said bars connected to said resistance conductor, others of said bars connected to terminals of said lamps, a contact rotatable about the axis of said insulating material adapted to engage said bars, and means extending to the exterior of said shell for rotating said contact.

9. The combination with an electric lamp, of a resistance coil, contact bars disposed parallel to the axis of said coil and connected thereto at different points, and a rotatable contact member controlling the circuit of

said lamp and comprising superposed similar contact elements having contact fingers, said elements being displaced with respect to each other to effect a spacing of said fingers similar to the spacing of said contact bars.

5 In testimony whereof I have hereunto af-

fixed my signature in the presence of the subscribing witnesses.

CHARLES WIRT.
